DESIGN FOR A FOUNTAIN PEN STAND

Philip C. Hall, Los Angeles, Calif.

Application May 13, 1940, Serial No. 92,329

Term of patent 7 years

To all whom it may concern:

Be it known that I, Philip C. Hall, a citizen of the United States, residing at Los Angeles, in the county of Los Angeles and State of California, have invented a new, original, and ornamental Design for a Fountain Pen Stand, of which the following is a specification, reference being had to the accompanying drawing, forming part thereof.

Fig. 1 is a front perspective of a fountain pen stand showing my new design,

Fig. 2 is an end elevational view thereof, and
Fig. 3 is a top plan view of the same.

I claim:

The ornamental design for a fountain pen stand, as shown.

PHILIP C. HALL.
